UNITED STATES PATENT OFFICE.

GEORGE H. KENT, OF WATERTOWN, MASSACHUSETTS.

COMBINATION-CARD FOR BANKING PURPOSES.

1,166,054.

Specification of Letters Patent.

Patented Dec. 28, 1915.

Application filed July 2, 1914. Serial No. 848,677.

To all whom it may concern:

Be it known that I, GEORGE H. KENT, a citizen of the United States, residing in Watertown, in the county of Middlesex and 5 State of Massachusetts, have invented an Improvement in Combination-Cards for Banking Purposes, of which the following description, in connection with the accompanying drawings, is a specification, like 10 characters on the drawings representing like parts.

This invention relates to a card system for banking, which is especially useful in banks handling the so-called Christmas club 15 accounts, wherein a member of the club deposits a given or predetermined amount at stated intervals, as for instance each week of the year, and draws out the same during the month of December.

20 The invention has for its object to provide a system in which the chance of error on the part of the bank is reduced to a minimum, and in which the work of keeping the accounts is also reduced to a minimum.

25 To this end, I have provided a card, which is issued by the bank and is composed of separable members, one of which is designed to be retained by the bank and the other by the club member or depositor.

30 For sake of distinction, one member of the combination card may be designated the bank's card, and the other member the member's card, and each card is provided with columns indicative of the months of a year,

35 and each column is provided with sub-divisions or spaces having therein figures indicative of the amount to be deposited for the week corresponding to said spaces. The bank's card is provided with a character in-

40 dicative of the class in which the depositor is enrolled, and with a serial number to identify the card, and may and preferably will be provided with a space for an application ticket or slip having thereon the sig-

45 nature and address of the club member. The member's card of the combination card is provided on its under side or surface with monthly columns and weekly spaces, corresponding to the columns and spaces

50 on the bank's card, and arranged, so that when the member's card is superimposed upon the bank's card, the said columns and spaces coincide, so that the amount deposited by the club member for each week may 55 be simultaneously punched in both cards, which eliminates errors on the part of the

bank. The member's card on its reverse or under side is also provided with the card number and with the class number or character, and said member's card is made narrower than the bank's card, so that when the member's card is superimposed on the bank's card, with the columns and spaces in register, the class number or character and the card number on both cards are visible to the bank official and can be compared at a glance, which reduces to a minimum the liability of error on the part of the bank. 60 65

The particular features of the invention will be pointed out in the claim at the end 70 of this specification.

Figure 1 is a plan view of a combination card embodying this invention with the application slip or ticket affixed thereto. Fig. 2, a plan of the combination card with 75 the member's card folded over upon the bank's card, and Fig. 3, a plan view of the combination card with the application slip or ticket removed therefrom.

Referring to the drawing, *a* represents the 80 bank's card and *b* the member's card of a combination card embodying this invention. The cards *a*, *b*, are formed of one piece of board or sheet of paper or other suitable material, which is provided with perforations 85

indicated by the heavy black lines *c*, so that the member's card *b* can be folded over upon the bank's card *a*, for purpose of punching the same initially, and can then be separated therefrom and given to the depositor or 90 member. The bank's card *a* is provided with parallel lines 10, which form a series of columns *d*, arranged transversely thereof and indicative of the months of the year, and said columns are subdivided into spaces 95

12 by parallel lines 13 extended lengthwise of the card. The spaces 12 are designed to have printed in them the day of the week on which the amount to be paid into the bank is due, and also numbers indicative of the amount to be paid on that day. The card is provided at the left of the spaces 100 12 with a margin 14 having printed thereon the serial number of the card, which in the present instance is 2005, which is also the member's number and in the margin 14 is also printed the character indicative of the class under which the member is enrolled, which in the present instance is class 1 A.

The card *a* is also provided at the top thereof with a blank space 15, see Fig. 3, and with cuts or slits 16 for the reception of the 105 110

application ticket, slip or card 17 shown in Fig. 1. The application card or slip 17 is separate from the combination card initially, and is designed to be filled out by the member when he or she makes application to join the Christmas club. The application card or slip 17 is provided with a class number and with the member's number, and is provided with suitable lines for the name and address of the member. After the application slip or ticket 17 has been filled out by the applicant, it is passed to the bank official, who affixes it to the card *a* of the combination card, by inserting the corners of the card in the slits 16. The club member deposits the amount due at the time the application is made, and the bank official folds the member's card *b* over upon the bank's card *a*, and punches the space 12 having printed thereon the amount deposited and the date of the deposit. Both cards, *a*, *b*, are punched simultaneously, and when punched the card *b* is separated from the card *a* and handed to the member, who retains it as a receipt for the money deposited by him. The bank retains the card *a* and files the same away. On the deposit day of the following week, the member presents his card *b* with the amount to be deposited to the bank official, who selects the bank's card *a* having the same serial number and also the same class number, and applies the card *b* to the card *a* after the manner shown in Fig. 2, and then punches the next space 12 in the column in which the space 12 has been already punched. It will be observed by

reference to Fig. 2, that when the card *b* has been applied to card *a* the serial number 2005 and the class number 1 A on both cards are visible and can be compared by a glance, and when compared, the payment or deposit is then punched simultaneously in both cards. From the above description, it will be seen that the chance for error on the part of the bank by applying to the bank's card *a* a member's card *b* other than the proper one, is reduced to a minimum. Also the work on the part of the bank officials is reduced to a minimum.

Claim:

A card of the character described, comprising a bank's card provided with means for attaching thereto an application card, a member's card, and means for detachably securing said member's card to said bank's card to permit the member's card to be folded over upon the bank's card while remaining attached thereto, the member's card being narrower than the bank's card to leave a portion of the latter visible when the member's card is superimposed upon the bank's card, both of said cards having thereon identifying devices which are simultaneously visible when the member's card is superimposed upon the bank's card.

In testimony whereof, I have signed my name to this specification in the presence of two subscribing witnesses.

GEORGE H. KENT.
